J. W. DURGIN, OF BANGOR, MAINE, ASSIGNOR TO E. Q. NORTON AND A. H. NORTON, OF THE SAME PLACE.

Letters Patent No. 65,185, dated May 28, 1867

IMPROVED MACHINE FOR CUTTING SLATE.

The Schedule referred to in these Letters Patent and making part of the same.

TO ALL WHOM IT MAY CONCERN:

Be it known that I, J. W. DURGIN, of Bangor, in the county of Penobscot, and State of Maine, have invented a new and improved Machine for Cutting Slate; and I do hereby declare that the following is a full, clear, and exact description thereof, which will enable those skilled in the art to make and use the same, reference being had to the accompanying drawings, forming part of this specification.

This invention relates to a new and improved machine for cutting slate for roofing purposes; and it consists of a knife attached to a suitable bed-piece, and of such a shape as to cut the slate in the form required, the knife being attached to the bed-piece by pivots, and operated through the medium of a lever or treadle, all arranged as hereinafter fully shown and described. In the accompanying sheet of drawings—

Figure 1 is a side view of my invention.

Figure 2, a plan or top view of the same.

Similar letters of reference indicate corresponding parts.

A represents a horizontal bed-piece, which is supported at a suitable height by legs *a* or any proper framing. The ends of this bed-piece are cut in a form corresponding to the shape designed to be given to the slate. In fig. 2, one end, *a*, is shown, of semicircular form, and the other end, *b*, of pointed form, similar to a gothic arch. This bed-piece is of wood, has its ends shod with metal bars *c*, and to each end of the bed-piece there is attached a knife, one knife, *B*, being of semicircular form, corresponding to the semicircular end *a* of the bed-piece, over which the knife works, and the other knife, *C*, fitted to the opposite end *b* of the bed-piece, so as to work over said end, and being of corresponding shape. These knives *B C* are secured, at their inner ends, to the bed-piece *A* by pivots *d*, a pivot passing into each side of the bed-piece. The outer parts of the knives are connected, by links *e*, to levers *D*, the fulcrum-pins *f* of which pass through pendants *g* attached to the under side of the bed-piece, each lever passing through a guide, *h*, secured to the under side of the bed-piece, said guide preventing the levers *D* being depressed or forced down beyond a certain point.

The pieces of slate to be cut are laid, one at a time, on the bed-piece *A*, on either end, according to the form or shape in which it is designed to cut them, the edges of the slate lapping over the edges of the bed-piece and the knife elevated above them. The knife is then drawn down over the slate, and the latter cut in form corresponding to the knife and the end of the bed-piece on which they are cut.

I would remark that the ends of the bed-piece may be of any desired form, according to the shape in which it is designed to cut the slate; and in lieu of levers treadles may be employed to bring down the knives upon them.

I claim as new, and desire to secure by Letters Patent—

The cutting of slate for roofing purposes, composed of a knife of a shape corresponding to that in which it is designed to cut the slate, and pivoted to the end of a bed-piece of a form corresponding to that of the knife, and of such dimensions that the knife may work over it, with a lever or treadle applied to the knife, all arranged substantially in the manner as shown and described.

J. W. DURGIN.
